UNITED STATES PATENT OFFICE.

CHRISTIAN FRIEDERICH, OF ELIZABETH, NEW JERSEY, ASSIGNOR TO THE
SINGER MANUFACTURING COMPANY, OF NEW JERSEY.

SEWING-MACHINE.

SPECIFICATION forming part of Letters Patent No. 545,882, dated September 10, 1895.

Application filed June 27, 1894. Serial No. 515,879. (No model.)

To all whom it may concern:

Be it known that I, CHRISTIAN FRIEDERICH, a citizen of the United States, residing at Elizabeth, in the county of Union and State of New Jersey, have invented certain new and useful Improvements in Sewing-Machines, of which the following is a specification, reference being had therein to the accompanying drawings.

10 In that class of sewing-machines in which an irregular feeding mechanism capable of moving goods backward as well as forward is employed in connection with the mechanism for moving the needle-bar laterally for the purpose of performing fancy stitching and in which the lateral movements of the needle-bar are controlled by a pattern-cam having an intermittent rotating movement imparted thereto from the continuously-rotating driving-shaft more or less difficulty has been experienced with the use of an ordinary pawl-and-ratchet mechanism for rotating the said pattern-cam by reason of the fact that where the cam is used in connection with a feeding mechanism for making a particular pattern an accidental backward turning of the driving-shaft by the operator or an accidental overthrowing of the pawl-and-ratchet mechanism for operating the pattern-cam will place the pattern-cam out of proper timing with the feeding mechanism, and thus render the machine inoperative for making the particular fancy stitch desired.

My invention has for its object to obviate the difficulty referred to, and this object is effected by the use of what may be termed a "positive ratchet mechanism," whereby a toothed wheel, to which the pattern-cam is attached and by which it is intermittently rotated, is at all times held positively either by its operating-dog or by a holding-dog which is caused to engage the teeth of the said wheel when the teeth of the operating-dog are released therefrom. The operating-dog and the teeth of the intermittently-rotated wheel are of such construction that if the direction of rotation of the driving-shaft should be accidentally reversed the movements of the toothed wheel and pattern-cam will also be reversed, and thus it will be impossible to get a pattern-cam which has once been properly set rela-

tive to the feeding mechanism and other parts of the machine out of timing.

In the accompanying drawings, Figure 1 is a side view, partly in section, of a fancy-stitch 55 sewing-machine embodying my invention. Fig. 2 is a bottom view of the same. Fig. 3 is a partial front view of the same. Fig. 4 is a partial longitudinal section through the arm, showing the mechanism inclosed therein in 60 side elevation. Figs. 5 and 6 are sectional views on line 5 6, Fig. 4, the parts being in slightly-different positions in the two figures. Fig. 7 is a detail view of the swinging sector and the dog carried thereby.

A denotes the bed-plate and B the bracket-arm of a well-known type of Singer sewing-machine. Journaled in the upper part of the bracket-arm is the driving-shaft C, provided at its rear end with the fly-wheel and pulley 70 c and at its forward end with a crank-disk c', connected by a link d with the block d', attached to the needle-bar D, said needle-bar having its vertical bearing in a laterally-movable frame D'. Secured to the driving-shaft 75 C is a cam-cylinder B', provided with cam-grooves b and b'. Mounted on a stud C', screwed into a web b² in the bracket-arm B, is a toothed wheel D², to which is attached a pattern-wheel D³, having a pattern cam-groove 80 d², which is entered by a pin or roller-stud e on the lever E, pivoted at its lower end at e' in a suitable bearing in bracket-arm B and provided in its front face with a groove e², in which is adjustably secured a pin f, connected 85 by a pitman F to an arm d³ on the pivoted needle-bar-carrying frame D', so that vibrating movements of the said lever E will impart lateral movements to the needle bar frame and the needle-bar carried thereby. Pivoted 90 on the hub d⁴ of the toothed wheel D² is a vibrating lever or sector G, which carries the operating-dog G', having at one end a rectangular tooth g for engagement with the rectangular teeth of the wheel D² and having at 95 its other end a pin g', which enters the cam-groove b' in the cam-cylinder B', said dog being pivoted at g⁵ to the said vibrating lever or sector G and the latter being connected by a link h with a lever H, having a pin h', entering the cam-groove b to impart vibrating 100 movements to the said lever or sector G, and

thus carry the said dog G' back and forth to intermittently rotate the toothed wheel D², the vibrating movements of the said dog on its pivot (imparted thereto by the grooved cam b') causing the tooth g to be engaged with and disengaged from the teeth of the said wheel at proper intervals.

I is a holding-dog pivoted at i to the bracket-arm B and provided at one end with a rectangular tooth i' for engagement with the teeth of the toothed wheel D² and having at its opposite end a slot i'', entered by a pin g³ on the operating-dog G', so that the said dog G' as it is vibrated by the cam b' will reversely operate the holding-dog, and thus as the tooth of the operating-dog is lifted from the teeth of the wheel D² the tooth of the holding-dog will be engaged with the teeth of said wheel, and vice versa. It will thus be seen that a tooth of either the holding-dog G' or the operating-dog I will always be in engagement with the teeth of the said wheel, and the latter will therefore always be positively held. The rectangular shape of the teeth of the wheel D² and of the tooth g of the operating-dog G' insures a positive hold by the tooth of the said operating-dog upon the teeth of the said wheel at all times, and if the shaft C be turned backward the operating-dog will therefore merely be reversed in its movements and will rotate the wheel D² backward, thus always keeping the pattern cam-wheel D³, which is attached to said wheel D², in proper timing with the other parts of the machine.

J is a vertical shaft placed within the vertical part of the bracket-arm B and provided at its upper end with a beveled gear-wheel j, meshing with a similar beveled gear-wheel c⁴ on the driving-shaft C, the said vertical shaft J having at its lower end a crank j', connected by a pitman J' with the shuttle-operating shaft K at the forward end of the machine in the usual manner with this style of machines. The shaft J is provided above the crank j' with a pinion k, which is connected by a train of gearing with the cam-wheel L, having a suitable cam-groove entered by a pin m on the bell-crank lever M, which latter serves to impart vibrating movements to the feeding-lever N, longitudinal movements being imparted to said feeding-lever by the usual cam on the shaft J for the purpose of raising and lowering the feed-bar O. The vibrating movements of the said feeding-lever N to move the feed-bar back and forth horizontally are controlled by the cam-wheel L, which may be provided with a cam-groove of any desired pattern, according to the fancy stitch which it may be desired to produce. This particular feeding mechanism is constructed to move the work backward at times, as well as forward, and is the same as heretofore employed in the fancy-stitch Singer machine, and is merely herein shown and described for the purpose of a full understanding of my invention, the essential feature of which is in the positively-rotated wheel D², which controls

the pattern-cam for moving the needle-bar laterally and which is capable of being moved either backward or forward, according to the direction of rotation of the driving-shaft, so that it will always be kept in time with the feeding mechanism controlled by the cam-wheel N.

From the foregoing it will be understood that when the machine is in operation intermittently-rotating movements will be imparted to the toothed wheel D² by the operating-dog G', said wheel being positively held either by the tooth g of the said dog or by the tooth i' of the holding-dog I, the pin-and-slot connection of the said dogs G' and I causing the tooth of the holding-dog to be engaged with the teeth of the said wheel when the tooth of said holding-dog G' is released therefrom, and vice versa. The swinging movements of the lever or sector G, imparted thereto from the cam-groove b through the lever H and link h, carries the operating-dog G' bodily back and forth, and therefore imparts an intermittent rotary movement to the said wheel, the vibrating movements of the said dog G', imparted thereto from the grooved cam b', causing the tooth of the said dog to be alternately engaged with and disengaged from the teeth of the said wheel. Owing to the fact that the toothed wheel D² will always be rotated either backward or forward, according to the direction of rotation of the driving-shaft, and also owing to the fact that said toothed wheel is always positively held by its operating-dog G' or by the holding-dog I it will be impossible for the cam-wheel operated by the said toothed wheel to get out of timing with the feeding mechanism or any other parts of the machine either by overthrowing movements of the said toothed wheel or by accidental reverse movements of the driving-shaft.

Having thus described my invention, I claim and desire to secure by Letters Patent—

1. In a sewing machine, the combination with a feeding mechanism, of a needle bar, a swinging frame in which said needle bar has its vertical movements, a cam wheel connected to said needle bar to impart lateral movements thereto, a toothed wheel by which said cam wheel is operated, a swinging sector or lever, a pivoted operating dog carried thereby and having a tooth for engagement with the teeth of the said wheel, two rotating cams one of which serves to vibrate said operating dog on its pivot to cause its tooth to be engaged with and disengaged from the teeth of said wheel and the other of which is connected with said swinging sector to move the latter and the operating dog carried thereby back and forth to intermittently rotate said wheel, a continuously rotating shaft on which said cams are mounted, a holding dog having a tooth for engagement with the teeth of said wheel, and means for operating said holding dog so that its tooth will be in engagement with the teeth of the wheel when the tooth of

the operating dog is disengaged therefrom, and vice versa.

2. The combination with the shaft C, of the needle bar operatively connected with the forward end of said shaft to be reciprocated vertically, a swinging frame in which said needle-bar has its vertical bearings, the toothed wheel D², the pattern cam-wheel D³ operated by said toothed wheel and connected with said needle-bar frame to move the latter horizontally, the cam cylinder B' carried by said shaft C and having the grooved cams b and b', the swinging sector or lever G, the lever H

operated by the grooved cam b, the link h connecting said lever H with said sector or lever G, the dog G' pivoted to said sector or lever and vibrated on its pivot by the grooved cam b, and the pivoted holding dog I having a slot and pin connection with said dog G', to be reversely operated thereby.

In testimony whereof I affix my signature in presence of two witnesses.

CHRISTIAN FRIEDERICH.
